GAME

Filed Dec. 23, 1922

2 Sheets-Sheet 1

FIG. 1.

DRIVER --- 150 TO 235 YDS.

MIDIRON --- 135 TO 190 YDS.

MASHIE --- 90 TO 135 YDS.

NIBLICK --- 15 TO 60 YDS.

MASHIE AND NIBLICK TO BE USED
INSIDE OF PUTTING GREEN AREA OR
OUTER CIRCLE --- USE PUTTING
CUBES ON PUTTING GREEN ACCORDING
TO THE CIRCLE THE BALL REACHES
IF OUTER CIRCLE USE RED CUBE
IF MIDDLE CIRCLE USE GREEN CUBE
AND IF THE CENTER CIRCLE,
USE BLUE CUBE

GAME

Filed Dec. 23, 1922

2 Sheets-Sheet 2

UNITED STATES PATENT OFFICE.

THOMAS H. SMITH, OF BLOOMINGTON, ILLINOIS.

GAME.

Application filed December 23, 1922. Serial No. 608,645.

To all whom it may concern:

Be it known that I, THOMAS H. SMITH, a citizen of the United States of America, and a resident of Bloomington, county of Mc-

Lean, and State of Illinois, have invented a new and useful Improvement in Games, of which the following is a specification.

The main objects of this invention are to provide an improved apparatus for playing indoors an outdoor game involving the knocking of a ball over a predetermined course or field; to provide an improved construction of means for representing in accurate miniature the course or field, or portions thereof, on which the outdoor game is played; to provide improved means representing the implements or paraphernalia with which the game is played on the course or field and indicating the "plays" which result from the use of such implements or paraphernalia; to provide an improved apparatus of this kind which is particularly adapted for use in playing golf; and to provide a golf game of this kind wherein, except for actually knocking the ball, the manner and results of playing closely resemble the playing and the scores of the outdoor game.

An illustrative embodiment of this invention is shown in the accompanying drawings, in which—

Figure 1 is a plan of a plate whereon is a miniature representation of a portion of a golf course, constructed in accordance with this invention.

Fig. 2 is a perspective view of the receptacle containing the "counters" by means of which a game, constructed in accordance with this invention, is played.

Fig. 3 is a perspective view of a dice cup which is used in "throwing" the counters.

Figs. 4 and 5 are enlarged views of the two faces of a triangular card board scale or measure adapted for use in aiding the players to make the "moves" on the plate shown in Fig. 1.

A game embodying this invention involves the use of one or more plates bearing representations of the playing field of an outdoor game wherein a ball is knocked over the field, and counting means for directing the "plays" to be made with the means which represent the ball.

On the plate or plates the representations of the field (or portions thereof) are laid out to scale showing the various characteris-

tics peculiar to the outdoor field. The plates may be, and preferably are, colored and shaded to more clearly visualize these characteristics.

The counting means comprises several pairs of cubes, or bodies having four or more sides, representative of the implements used in the outdoor game. Said bodies bear descriptive indicia on the faces thereof such that when said bodies are "thrown" in various groups the indicia thereon combine to directly indicate the "play" that should be made on the plate 1.

In the specific embodiment herein shown, the apparatus is constructed for use in playing golf. The golf course is preferably laid out on several different plates, each plate representing the course between a tee and a hole, or one plate containing the representation of several such portions of the course, particularly the shorter ones.

The plate 1 shown in Fig. 1 is more or less characteristic of all of the plates. The representation is drawn to scale and shows an actual golf course with its fairway 2, between the tee 3 and hole 4, the fairway being bordered with the "rough" portions 5 and 6 of the field. Sand traps 7, bunkers 8, and stymies 9, are illustrated on the plate to correspond with the arrangement of the course of which this representation purports to be a miniature. Preferably the plate has the fairway 2 colored green and the sand traps 7 colored yellow, as indicated by the cross-hatching in the drawings. The "rough" portions 5 and 6 and the bunkers 8, in addition to being tinted green, are preferably heavily shaded so as to represent elevations.

The stymies 9 may also be tinted and have trees drawn thereon. A dotted line 10 is drawn along the middle of the fairway 2 and at intervals therealong has transverse lines marked to represent distances on the fairway.

In this representation the hole 4 on the "green" is circumscribed by three circles 4^B, 4^G and 4^R outlining zones, each extending around the hole, and within which the number of strokes to "hole out" are determined directly from a special counter rather than by the number of plays made by the player using the other counters as in the case when playing on the "fairway," as will be more clearly hereinafter pointed out.

The material for use in playing the game is shown in Figures 2 to 5, and comprises

means 11 representing the "golf balls," counters 12 representing the "clubs," and a measuring scale 13 for use in measuring distances on the plate 1.

5 The means 11 for representing the "balls" are in the nature of small dome-shaped blocks preferably colored white, and numbered in pairs. These are to be set along on the plate 1 as directed by the counters to 10 indicate the "plays" along the course.

The counters comprise a plurality of bodies each having four or more sides, as for example the cubes 12, which answer a purpose similar to dice, two of such bodies 15 being arranged to represent each of the "clubs" used in the outdoor golf game, such as for example, the driver, the mid-iron, the mashie, etc. Three of such bodies represent the putters.

20 Each of said bodies bears on its several faces descriptive indicia, which consists of the name of the "club" which said bodies represents, and figures indicative of yards, distance, or strokes, the latter being characteristic only of the "putter" bodies. In

25 addition to this, one of said bodies of each pair has indicia indicating directions along the course, either "straight," "slice," or "hook." The figures are of varying

30 amounts, being proportioned between the minimum and maximum yards which a ball is driven by the various clubs when actually used in the outdoor game. For example, in Fig. 2, the three exposed faces of one of the bodies 12 intended to represent the "driver," bear the figures 185, 220 and 235 respectively. These figures correspond with the number of yards to be measured along the center line 10 of the fairway 2. The other

35 of such bodies representing the "driver," shows on one face that the direction of the drive is straight, and on the other, that the stroke resulted in a fifty-yard "slice." Other faces of this same body 12 show either

40 a "slice" or a "hook," as do also the other corresponding bodies as will be readily observed from Fig. 2.

The bodies 12 which represent the putters are three in number, and are variously differentiated as by being colored red, green, and blue, for the purpose of readily indicating which one is to be used when the "ball" is approaching the "green" and within one or the other of the zones indicated by the

50 circles 4^R, 4^G, or 4^B. The numbers on these bodies indicate the "strokes" required to "hole in" rather than distance. The numbers appearing on the several sides or faces of these bodies are varied so as to nearly

55 represent the probabilities of "holing in" in the regular outdoor golf game. Thus, the putter body which is to be used when the "ball" is within the circle 4^R, has more sides or faces with a larger number on them, than

60 the body which is to be used when the "ball"

11 is in the innermost circle 4^B. For example, the cube 12^R, has the figure 3 on three faces, the figure 2 on two faces, and the figure 1 on one face, and is used when the "ball" 11 is within the circle 4^R. Cube 12^B 70 has the figure 1 on four faces, the figure 2 on one face, and the figure 3 on another face, and is intended for use when the "ball" 11 is in the innermost circle 4^B. The other cube has the figure 2 on four faces, the figure 1 on one face, and the figure 3 on another, and is intended for use when the "ball" is 75 within the circle 4^G.

A block 14, called the "caddie," is provided with a plurality of pockets or recesses 15 adapted to contain the cubes 12 and the "balls" 11. These pockets are marked, as shown in Figure 2, to represent the various clubs used in the outdoor game.

80 The usual dice cup 16 is provided for use in shaking and throwing the cubes 12.

The scale or measure 13, in the form of a heavy piece of cardboard or similar material, is cut triangular shape and provided with scales along the three edges thereof, which scales correspond with the scale used in making the representation on the plate 1. On one side along one of the right angle edges, the scale indicates "distance," as at 17, and along the other right angle edge, indicates "slice," as at 18. On the other face, along the same edges, the scale represents "distance," as at 19, and "hook," as at 20. Along the hypotenuse on each side the scale represents "distance." By the use of this measure or rule, the players can quickly measure distances between those marked on the plate 1 and the distance to the right and left of the center line 10 to correspond to the "slice" and "hook" indicated on the cubes.

100 The game herein shown and described is played in substantially the following manner:

105 The rules governing the playing of this indoor game are the same as those for playing the outdoor game.

110 Each player has his own "caddie" 14 and, starting with the plate 1 representing the first hole of the course, in turn shakes and throws first the two cubes representing the "driver" and then another pair of cubes representing another club, depending on the result of the "play" made with the "driver" cubes.

115 The indicia on the two upper faces of each pair of cubes thrown indicates the distance which the "ball" is driven and the direction, that is, whether it is straight or to the left or right of the center line. If, for example, this indicia on the "driver" cubes reads 220 on one cube and 50 "hook" on the other, the "ball" 11 of that player is placed on the "fairway" 220 yards away from the tee, and 50 yards to the left of the center line 10.

120 Unless this puts the "ball" 11 over in 125 130

the "rough," when it again becomes this player's turn to play the two dice representing the mid-iron are shaken and thrown and the "ball" moved on down the course the distance and direction indicated by this throw. If, however, the "ball" goes into the "rough" or into one of the sand traps, the cubes representing the club which, in the outdoor game is generally used to get a "ball" out of the "rough" or trap, are thrown and the ball moved in accordance with the figures on the uppermost faces of such cubes.

When the "ball" 11 is within any one of the three circles, one or the other of the cubes representing the putters is used, and the figure on the uppermost face of the cube thrown, represents the number of strokes to be counted in "holing" the "ball."

20 A score card is kept the same as in regular outdoor golf, and each player plays in his turn the same as if he were playing outdoors.

Although but one specific embodiment of this invention has been herein shown and described it will be understood that numerous details of the construction shown may be altered or omitted without departing from the spirit of this invention as defined by the following claims.

I claim:

1. An indoor golf game comprising a plate having represented thereon the "fairway" and border portions of a field of the outdoor game between a tee and a hole, a plurality of circles circumscribed about the point representing the hole, means movable over said plate to represent the "plays" in driving the ball from the tee to the hole, a plurality of pairs of cubes representing the different clubs used in the outdoor game, said cubes bearing descriptive indicia on the faces thereof and being adapted to be used in pairs whereby the indicia on the face of one cube indicates the distance, and the indicia on the other cube indicates the direction, which said means should be moved along said "fairway" as representative of the stroke which the player would make with a corresponding club in the outdoor game, a plurality of other cubes corresponding in number with the number of said circles around said hole, said cubes bearing descriptive indicia on the faces thereof and being adapted to be used singly whereby the indicia on one face indicates the number of strokes to "hole" a ball from within the corresponding circle, as representative of the strokes which the player would make with a "putter" in the outdoor game.

2. An indoor golf game comprising a plate having represented thereon the "fairway" and border portions of a field of the

outdoor game between a tee and a hole, a plurality of circles circumscribed about the point representing the hole, means movable over said plate to represent the "plays" in driving the ball from the tee to the hole, a plurality of pairs of bodies having four or more sides representing the different clubs used in the outdoor game, said bodies bearing descriptive indicia on the sides thereof and being adapted to be used in pairs whereby the indicia on the sides of one of said bodies indicates the distance and the indicia on the other of said bodies indicates the direction, which said means should be moved along said "fairway" at representative of the stroke which the player would make with a corresponding club in the outdoor game, a plurality of other bodies having four or more sides corresponding in number with the number of said circles around said hole, said bodies bearing descriptive indicia on the sides thereof and being adapted to be used singly whereby the indicia on one side indicates the number of strokes to "hole" a ball from within the corresponding circle, as representative of the strokes which the player would make with a "putter" in the outdoor game.

3. An indoor golf game comprising a plate having represented thereon the "fairway" and border portions of a field of the outdoor game between a tee and a hole, a plurality of zones each extending around the point representing the hole, means movable over said plate to represent the "plays" in driving the ball from the tee to the hole, a plurality of pairs of bodies having four or more sides representing the different clubs used in the outdoor game, said bodies bearing descriptive indicia on the sides thereof and being adapted to be used in pairs whereby the indicia on the sides of one of said bodies indicates the distance, and the indicia on the other of said bodies indicates the direction, which said means should be moved along said "fairway" as representative of the stroke which the player would make with a corresponding club in the outdoor game, a plurality of other bodies having four or more sides corresponding in number with the number of said zones around said hole, said bodies bearing descriptive indicia on the sides thereof and being adapted to be used singly whereby the indicia on one side indicates the number of strokes to "hole" a ball from within the corresponding zone, as representative of the strokes which the player would make with a "putter" in the outdoor game.

Signed at Chicago this 18th day of December, 1922.

THOMAS H. SMITH.
